UNITED STATES PATENT OFFICE.

EDWARD L. CALEY, OF PHILADELPHIA, PENNSYLVANIA, ASSIGNOR TO GILBERT COMBS, JOHN BAWDEN, AND JOHN H. BAWDEN, OF FREEHOLD, NEW JERSEY.

DESIGN FOR A PORTABLE FIRE-PLACE GRATE.

SPECIFICATION forming part of Design No. 19,147, dated June 11, 1889.

Application filed January 9, 1889. Serial No. 295,886. Term of patent 7 years.

To all whom it may concern:

Be it known that I, EDWARD L. CALEY, a citizen of the United States, and a resident of Philadelphia, Pennsylvania, have invented 5 a new and original Design for a Portable Fire-Place Grate, of which the following is a specification.

My design is fully shown in the accompanying photographic illustration.

10 The general design of the back and side plates is of the character of a foliated scroll, the design of the front plate being of an open-work character. On the back plate is a panel with border-line having scroll-work ornaments 15 at the corners. In the panel is a foliated design of scroll-like character with central rosette above, below and on each side of which are smaller rosettes. The side plates of the grate are ornamented with characters substantially similar to those of the back plate. The front plate is divided into three sections, 20 the central section being composed of four sets of zigzag bars joined together by verti-

cal bars, and the end sections are composed of horizontal continuations of these zigzag 25 bars connected together by vertical bars forming quadrangular spaces.

I claim—

1. In a design for a fire-place grate, the design for the back plate, said design consisting of the bordered panel with foliated scroll-like and rosette ornamentation, substantially as described, and as shown in and by the accompanying photographic illustration.

2. The design for a fire-place grate, substantially as described, and as shown in and by the accompanying photographic illustration.

In testimony whereof I have signed my name to this specification in the presence of two subscribing witnesses.

EDWARD L. CALEY.
